[57] **CLAIM**

The ornamental design for a disposable receptacle for a needle and syringe destructor, as shown and described.

DESCRIPTION

FIG. 1 is a perspective view of a disposable receptacle for a needle and syringe destructor embodying our new design showing a slidable door in the top thereof in an open position;

FIG. 2 is a perspective view of the disposable receptacle for a needle and syringe destructor showing the slidable door in the top thereof in a closed position;

FIG. 3 is a front elevational view thereof;

FIG. 4 is a rear elevational view thereof;

FIG. 5 is a bottom plan view thereof;

FIG. 6 is a cross sectional view taken substantially

along line 6—6 of FIG. 5 showing the door in the closed

position;

FIG. 7 is an exploded perspective view thereof.

FIG. 1
